Invention,

HENRI ROBERT PHILIPPE

D. Jones, Addington, Ames & Leibold
Atty.

UNITED STATES PATENT OFFICE.

HENRI ROBERT PHILIPPE, OF PARIS, FRANCE, ASSIGNOR TO FELIX COUNE, OF CHICAGO, ILLINOIS.

APPARATUS FOR THE EASY CLAMPING OF THE PROTECTING TUBES USED IN PERMANENT WAVING OF THE HAIR.

Application filed November 14, 1922. Serial No. 600,885.

To all whom it may concern:

Be it known that I, HENRI ROBERT PHILIPPE, a citizen of the French Republic, residing 400 Rue Saint-Honoré, Paris, France, have invented new and useful Improvements in an Apparatus for the Easy Clamping Near the Scalp of the Protecting Tubes Used in the Methods for the Lasting or Permanent Waving of the Hair on the Head, of which the following is the specification.

This invention relates to an apparatus for easily clamping, near the scalp, protecting tubes used in the methods for the permanent waving of hair.

As is well known, it is indispensable that this clamping should be effected in a perfect manner, so as to prevent any issue of steam near the head of the patient. For effecting this clamping, use has first been made of a resisting string, tightly stretched by means of special pliers. But this means has a serious inconvenience which becomes manifest when the hairdresser desires to release the lock of hair which has just been heated; in order to do this, it is necessary to open the tube at the end remote from the head, to split it throughout its length and then to cut the string, with precaution, so as not to injure the hair.

The invention has for its object an adjustable clamping apparatus of this kind, but the operation of which is much more rapid and the construction more simple and stronger than those having a screw and nut clamping system.

This apparatus is characterized in that the clamping, in variable position, of the branches strongly jointed together, is effected by simple pressure of the fingers on levers forming extensions of the said branches, while a locking system prevents any relative rotation of the branches in reverse direction, the unlocking taking place by exerting on the levers stresses parallel to the axis of rotation, so as to space apart the two branches which are made for that purpose of a metal having a sufficient resiliency.

The accompanying drawing illustrates, by way of example, a form of carrying out the invention.

Fig. 1 is an elevation of the apparatus in the open position.

Fig. 2 is a corresponding plan view, the apparatus being closed. 55

Fig. 3 is a section according to line 3—3 of Fig. 2.

Fig. 4 shows the method of using the apparatus.

Fig. 5 shows a constructional modification. 60

The device illustrated is composed of two branches *a* and *b* jointed at *c* and having an approximately semicircular shape. This shape, moreover, is not essential; it suffices that, in the closed position, these two branches provide between them an approximately circular hole in which the tube is clamped. 65

One of the branches *a* carries a tenon *d* 70 which combines with holes *e* formed in the other branch *b* and the centers of which are situated on an arc of a circle having for center *c*. The tenon *d* is, moreover, so cut as to present an incline *g* for permitting the 75 clamping, under the pressure of the fingers exerted according to the arrows *f* on the levers *h* and *k*. The branches are formed of a resilient metal, such as steel, the slope *g* compelling in fact the tenon *d* to lift the 80 branch *b*. On the other hand, for any stress directed in reverse direction to the arrows *f*, the tenon *d* remains in the holes *e* and thus forms a bolt preventing the unclamping. 85

For unlocking, it is necessary to move the branches apart by a pull exerted parallel to the axis *c* according to the arrows *f'*.

In practice, the tenon *d* instead of being secured in position, can be obtained by a 90 suitable stamping of the branch *a* (Fig. 5). The levers *h* and *k* are each provided with a surface *h'* and *k'* at right angles to the plane of the branches *a* and *b*, for facilitating their manipulation; this surface can be 95 obtained either by folding down a side tongue (Fig. 4) or by torsion of the levers *h* and *k* (Figs. 1, 2 and 3).

What I claim as my invention and desire to secure by Letters Patent is:

In combination with a heating tube for a hair waving appliance, of a clip and a scalp

protector comprising a pair of clamping levers hinged at one end, said levers being provided at the other end with operating handles, and means intermediate said handles and hinge adapted to hold the clamping levers around the end of the tube adjacent to the scalp, whereby the tube will

be sealed and the scalp protected from the heat applied to the tube during the hair waving operation.

In testimony whereof I have signed my name to this specification.

HENRI ROBERT PHILIPPE.
